Primary Examiner—Martie Thompson*Attorney, Agent, or Firm*—Kolisch, Hartwell, Dickinson, McCormack & Heuser[57] **CLAIM**

The ornamental design for a display stand, as shown and described.

DESCRIPTION

FIG. 1 is a top plan view of a display stand showing my new design;

FIG. 2 is a bottom plan view;

FIG. 3 is a front elevational view;

FIG. 4 is a rear elevational view;

FIG. 5 is a side elevational view, the side not shown being a mirror image thereof; and,

FIG. 6 is a perspective view thereof, the rectangular planar material therein being depicted by means of broken lines for illustrative purposes only and forming no part of the claimed design.

FIG.1

FIG.2

FIG.3

FIG.4
